REGISTER CASING DOOR

Richard H. Colwill, Chicago, Ill., assignor to
 United Autographic Register Co., a corporation
 of Illinois

Application May 3, 1937, Serial No. 140,531

5 Claims. (Cl. 282—12)

This invention relates particularly to an improved door for holding slips of stationery in a storage compartment of an autographic register and facilitating the removal of the slips when desired.

The primary object of the invention is to provide a simple and inexpensive device which may form part of the bottom wall of the register and when opened serve to bend the slips downwardly where they may be grasped for withdrawal.

The invention is illustrated in a preferred embodiment in the accompanying drawing, in which:

Figure 1 is a longitudinal sectional view of a machine embodying the invention; Fig. 2, a bottom plan view of the same; Fig. 3, an enlarged broken sectional view showing the trap door in opened position; and Fig. 4, a front elevational view of the machine.

20 In the embodiment illustrated A designates an autographic register casing having a supply compartment A' and a storage compartment A²; B, a suitable registering and initial feed device; and C, a trap door for the storage compartment A².

25 The casing of the register is of known construction having a bottom wall 5, a platen forming top 6, a partition 7 separating the supply compartment A' from the storage compartment A², and a skeleton cover 8 which is hinged to the bottom wall of the casing at 9 and has side walls which serve to enclose the platen and underlying mechanism. A suitable lock 10 serves to hold the cover in closed position.

As shown in Fig. 1, the record compartment 35 is provided with an adjustable abutment 11 which may be moved back and forth along the slot 12 to adjust the length of the compartment A'. In like manner, the storage compartment A² is provided with an abutment 13 which is held in position by a screw 14 slidably mounted in a slot 15 provided in the bottom wall 5.

No invention is claimed herein in the registering and initial feed device B which has register pins 16 which are urged upwardly to engage perforations in stationery drawn from the supply compartment over the platen 6. The mechanism is provided with a front handle 17 which is adapted to swing the pins forwardly so that ends of the stationery strips may be grasped by hand and drawn outwardly to a position where they may be severed on the tear-off edge 18 provided on the skeleton cover 8.

50 All of the above structure is known in the art and no invention is claimed herein. However, as best shown in Figs. 1, 3, and 4, the front end

of the skeleton cover member is provided with a cross-curved fixed guide 19 disposed above a fixed cross-bar 20 to provide a slip-admitting slot 21.

The front portion of the bottom wall 5 is cut away and provided with the trap-door C which is connected to the bottom of the casing by means of a traverse hinge 22. A stop member 23 is provided to limit the downward travel of the door, as indicated in Fig. 3. A keeper 24 has its end portions turned downwardly and outwardly 10 and is fixedly connected to the trap-door by means of rivets 25. The front end portion of the partition 7 is cut away adjacent to the guide member 19 so that the keeper may extend upwardly beyond the slip-admitting slot 21.

15 The trap-door is provided with outwardly extending arms 26 to which are connected tension springs 27 which serve to yieldingly hold the trap-door in either its fully opened or fully closed position. As shown in Fig. 1, the front 20 end portion of the trap-door is urged upwardly against the cross-bar 20 and is inclined upwardly from the plane of the bottom wall 5. Thus it will be understood that when a record slip is projected through the slot 21, it will slide by gravity 25 rearwardly to the abutment 13 and its front end will rest on the top of the cross-bar 20. The door is then flipped downwardly and upwardly so that the keeper 24 will draw the end of the slip beneath the cross-bar 20 where the slip will 30 be held in position even though the machine is turned up on an end. The front end portion of the trap-door is provided with a finger opening or notch 28 to facilitate grasping the ends of the slips when the trap-door is swung open. In this 35 position the ends of slips which have been projected into the storage compartment will be drawn downwardly by the keeper 24 so that they may all be withdrawn together and will remain in the same order in which they were filed.

40 The foregoing detailed description has been given for clearness of understanding only, and no unnecessary limitations should be understood therefrom, but the appended claims should be construed as broadly as permissible, in view of 45 the prior art.

I claim:

1. A portable autographic register casing having a record compartment in the base of said casing, said record compartment being provided at 50 its front end with a fixed slip-admitting slot and having a rearwardly hinged trap-door forming part of the bottom wall of said record-compartment and permitting access to the contents thereof, a stop for limiting the downward swing 55

of said door, and spring means for urging said door to either of its closed or fully opened positions.

2. A device as specified in claim 1, in which the trap-door in closed position is inclined upwardly beyond the plane of the bottom wall, and said door being provided with a keeper extending upwardly beyond said slot and having a finger opening to facilitate removal of slips from said compartment when the door is opened.

3. In a machine of the character set forth: a casing provided in its lower portion with a storage compartment, said compartment being provided near its front end with a pair of fixed guides spaced to provide a slip-admitting slot and having a hinged trap-door beneath said slot forming part of the bottom wall of the casing and adapted to swing downwardly to open said compartment, said door being provided with means for holding it up normally in closed position.

4. In a machine of the character set forth: a casing provided in its lower portion with a storage compartment, said compartment being

provided with a slip-admitting slot and having a hinged trap-door beneath said slot forming part of the bottom wall of the casing and adapted to swing downwardly to open the compartment, said door being provided with means for holding it normally in closed position, and said door having an upwardly extending keeper adjacent to said slot to embrace slips projected into the storage compartment.

5. In a machine of the character set forth: a casing provided in its lower portion with a storage compartment, said compartment being provided with a slip-admitting slot and having a hinged trap-door beneath said slot forming part of the bottom wall of the casing and adapted to swing downwardly to open the compartment, said trap-door being provided with means for holding it up normally in closed position, and said door having a keeper extending upwardly beyond said slot so as to embrace stationary slips deposited in said compartment and bend them outwardly when the door is opened.

RICHARD H. COLWILL.
